UNITED STATES PATENT OFFICE.

GEORGE FOSTER PEARSON, OF LOWELL, MASSACIUISETTS.

DESIGN FOR A FRAME FOR INDICATORS.

SPECIFICATION forming part of Design No. 32,739, dated May 29, 1900.

Application filed April 6, 1900. Serial No. 11,901. Term of patent 3½ years.

To all whom it may concern:

Be it known that I, GEORGE FOSTER PEARSON, a citizen of the United States, and a resident of Lowell, in the county of Middlesex and State of Massachusetts, have invented and produced a new and original Design for the Frame of an Indicator; and I do declare the following to be a full, clear, and exact description of the invention, such as will enable others skilled in the art to which it appertains to make and use the same, reference being had to the accompanying drawing, which forms a part of this specification.

The drawing is a front elevation or face view of my indicator-frame.

The invention has relation to a design for an indicator-frame; and it consists in the

novel form and configuration of parts, as hereinafter set forth.

As shown in the drawing, the leading or principal feature of the design consists of a circular field located between the legs of a figure having the general shape of a horseshoe-magnet.

What I claim, and desire to secure by Letters Patent, is—

The design for the frame of an indicator substantially as shown and described.

In testimony whereof I affix my signature in presence of two witnesses.

GEORGE FOSTER PEARSON.

Witnesses:

GEORGE M. ANDERSON,
HARRY L. AMER.
